LIQUID PUMP

Thomas L. Titus, Cheyenne, Wyo., assignor to
The Wyott Manufacturing Company, Chey-
enne, Wyo., a corporation of Wyoming

Application June 1, 1937, Serial No. 145,648

10 Claims. (Cl. 221—102)

My invention relates to pumps for liquids and, in its herein disclosed embodiment, particularly to pumps for dispensing predetermined quantities of liquids such as cream, syrups and the like. The invention will be herein described in terms of its structure and use for dispensing cream in predetermined quantities sufficient to fill the individual cream containers commonly used in restaurants and, in this regard, it is an improvement upon the dispenser which is the subject matter of my United States Patent No. 1,805,790 issued May 19, 1931.

Objects of my invention are, in a device of this class, to provide means (a) for positively controlled uniformity of speed of ejection of the liquid; (b) for predetermining the maximum quantity of liquid which can be ejected by any one operation; (c) for preventing spilling or spraying of liquid during ejection and preventing dripping or leakage of liquid; (d) for ejection of the predetermined amount of liquid by gravity, of the liquid accelerated by weight of a piston; (e) for convenient operation by the operator's hand which holds the container into which the liquid is to be ejected; (f) for recharging the device by the manual operation which automatically results in ejecting the charge; (g) for accomplishing these objects with a minimum of moving parts, with a structure of utmost simplicity of construction and operation and a structure which facilitates complete cleansing and sterilization and renders practically impossible the incorrect assembling of parts.

With these and other objects in view, all of which will more fully hereinafter appear, the invention comprises certain novel constructions, combinations and arrangements of parts as hereinafter described and claimed and as illustrated in the accompanying drawing in which like characters of reference indicate corresponding parts throughout and in which

Fig. 1 is a central longitudinal section of the device showing certain parts in elevation and illustrating the moving parts at rest in normal position between operations.

Fig. 2 is a central, longitudinal section taken at right angles to Fig. 1 and illustrating the moving parts at the extreme of the upward movement of piston and cylinder.

Fig. 3 is the same as Fig. 2 except that the parts are illustrated in position nearing the end of the downward or ejecting movement.

Fig. 4 is an illustration of a modification of structure in which the device is incorporated in the fluid reservoir.

Fig. 5 is a section on line 5—5 of Fig. 6 and Fig. 6 is a detail of the spout valve and fragment of associated parts on enlarged scale and in section showing valve closed as at the end of the ejecting operation.

My dispenser comprises a cylindrical housing in two parts designated as base 1 and top 2 connected by a ground joint as at 3. This housing is provided with a tubular boss or nipple 4 through which fluid is admitted to the housing from any suitable reservoir, not shown.

To clamp together parts 1 and 2 of the housing and also to provide an air outlet and seal therefor, I provide a yoke 5, suitably pivoted in part 1 of the housing, as at 6, and carrying centrally, a threaded pin 7 having suitable knurled head 8 and a conical point 9 adapted to seat in conical recess 10 in boss 11 projecting upwardly from the center of the top of part 2 of the housing and thereby clamp parts 1 and 2 together and, coincidentally, close air passage 12 leading from the interior of the housing through boss 11.

The floor of base portion 1 of the housing is provided with a frusto-conical recess 13, the wall of which forms a seat for the boss 14 projecting from the bottom of floating cylinder 15 positioned within the housing. The cylinder 15 is of less diameter than the interior of the housing leaving an annular chamber 16 for liquid circulation between the housing wall and the wall of cylinder 15, which is somewhat shorter than the length of the interior of the housing so as to allow some reciprocation of the cylinder within the housing. Suitable means, as lugs 17, project from the top of cylinder 15, to insure maintenance of passage way for liquid between chamber 16 and the upper interior of cylinder 15 even when the cylinder is at the extreme of its upward movement.

When the cylinder 15 moves downwardly boss 14 will be seated on the inclined wall of recess 13.

Boss 14 is provided with passage ways 18 for permitting passage of liquid, therethrough, into and out of the lower interior of cylinder 15. The boss 14 is also provided centrally thereof with a bore 19 in which piston stem 20 is slidable. The stem 20 is multifaced, preferably squared, with rounded edges 21, between the faces 22. This structure provides for a definitely guided reciprocation of stem 20 within bore 19 and also additional passageways for liquid into and out of the lower interior of cylinder 15 through bore 19 along faces 22.

Stem 20 carries, at its upper end, a piston head 23 having a relatively thin peripheral edge 24 having a substantially cream-tight but freely

sliding fit in the smaller bored portion 25 of cylinder 15, the cylinder having a larger bore 26 at the bottom for allowing free passage of cream around the periphery of head 23 when the head 5 is within the larger bore 26. Except near edge 24 head 23 is thickened as necessary to provide the desired weight for speeding the ejection of the cream as hereinafter described.

Depending centrally from base 1 of the housing I provide sleeve 27, the bore of which is of the same diameter as bore 19 and stem 20 extends down into sleeve 27 and has a sliding fit therein and cream passageways along the faces 22 thereof within sleeve 27 substantially the 15 same as within bore 19, as above described. Stem 20, slidably mounted in sleeve 27 and in bore 19 as above described, serves to position cylinder 15 centrally within the housing at all times.

20 Spout 28 is slidably mounted within the lower end of sleeve 27, the bore of the sleeve being suitably reduced as at 29 and 30 to provide such 25 slideable mounting and also to provide a seat 31 for rim 32 of the spout, which rim has a slideable but cream tight fit in the bore of sleeve 27. The top of spout 28 is interiorly bevelled as at 33 to form a valve seat for conical valve 34 on the lower end of stem 20.

20 The spout 28 projects below sleeve 27 to a suitable distance for adjustment and operation as hereinafter described. The lower end of spout 28 is reduced to a sharp edge preferably by rounding the outside thereof as at 35.

Slidably mounted on the lower end of spout 28 35 I provide operating nut 36 adapted to be set at any desired point along the spout by suitable means as set screw 37 and having enlarged bore 38 in its lower portion to substantially clear the nut from contact with the spout at or adjacent the lower end of the spout. The bottom of nut 36 is cone shaped as at 39 to accommodate the neck of an ordinary, individual service cream container as indicated in broken lines.

The modified embodiment illustrated in Fig. 45 4 is the same as the structure above described with the following exceptions, viz: instead of a 50 separate reservoir connected with the housing by conduit 4, I here provide the reservoir integral with the housing by enlarging the upper part thereof as at 40, providing therefor any suitable 55 top or cover not shown. As the upper interior of cylinder 15 is always open to the cream in the reservoir the lugs 17 may be eliminated. The ground joint 3 is not essential but is preferably 60 provided for affording convenient access to the bottom of the interior of the housing. The weight of the reservoir 40 will be sufficient to prevent undesired disconnection at the joint thereby rendering yoke 5 unnecessary. No cover 65 valve being required in this structure parts above described from and including screw 7 to and including air passage 12 are here eliminated.

The operation of the device will now be described.

65 Starting with the device assembled as illustrated in Fig. 1, the cream flows in from the reservoir, not shown, through tubular boss 4 and fills the interior of the housing at all points above the bottom of boss 14, which is seated on the 70 wall of recess 13 and the cylinder 15. During the filling of the housing the air is exhausted through passage 12 which is opened by raising screw 7. When the housing is filled, passage 12 is closed by returning screw 7 to position shown 75 in Figs. 1, 2 and 3.

Nut 36 is set at that point on spout 28 which will give the desired length of stroke and corresponding size of ejected charge, as hereinafter described. The nut is fixed at this point by set screw 37.

5 Nut 36 is now forced upwardly until it is stopped by the lower end of sleeve 27 as illustrated in Fig. 2. This lifting of nut 36 is done by any suitable means but, where the ordinary individual size cream container is to be filled, the 10 operation is most conveniently accomplished by the operator applying the container to the cone shaped bottom 39 of the nut in the manner illustrated in Fig. 2 where the container is indicated in broken lines. The upward pressure 15 raises nut 36, spout 28, stem 20 and piston head 23 to the positions illustrated in Fig. 2.

During this movement, so long as edge 24 of the piston head is within large bore 26 of cylinder 15, the cream from above the piston will pass 20 freely around edge 24 into the space below piston head 23 but when edge 24 moves into the smaller bore 25 of cylinder 15, passage of cream around edge 24 is shut off and during the balance 25 of the upstroke of piston head 23 pressure is exerted on the cream above head 23 and suction is set up below the head. This action lifts cylinder 15 until lugs 17 contact the ceiling of the housing. The cream compressed in the upper interior of cylinder 15 flows over the top into an 30 annular chamber 16, freely until the lugs strike the ceiling and thereafter between the lugs, and the cream in the lower part of chamber 16 flows beneath the cylinder filling the interior of the cylinder below the piston head as well as passages 35 18 and the passages along faces 22 of stem 20, both within boss 14 and as far down as valve seat 33, which is closed by cone 34.

When piston head 23 reaches the limit of its upstroke the pressure above and the suction below the head cease and the cylinder drops of its own weight, seating the lower edge of boss 14 on the wall of recess 13 and thus shutting off the inflow of cream beneath the cylinder.

When upward pressure on nut 36 is released 45 the nut and spout 28, affixed thereto by set screw 37, will drop to position shown in Fig. 3 thus opening valve 33—34 and seating rim 32 on seat 31 and permitting the cream below head 23 in cylinder 15, passages 18 and spaces around stem 50 20 to flow down through and out of spout 28 into the container.

This down flow of cream will result from the weight of the cream itself but will be accelerated by the weight of stem 20 and head 23 which are 55 preferably made of comparatively heavy material, the head being thickened to any degree desired for the increase of weight. The weight may be varied according to the thickness or viscosity of the liquid which the device is designed to handle. 60

The acceleration of the downflow of the cream by the weight of the stem and head will continue until edge 24 has passed into large bore 26 whereupon the resistance of the cream to the downward movement of the head, with its depending 65 stem, will be removed because the cream can freely pass upwardly around edge 24. Accordingly, when edge 24 passes into larger bore 26 the head 23 and the stem 20 will drop, without substantial resistance, until cone 34 is seated 70 in seat 33. The closing of valve 33—34, as just described, instantaneously cuts off the flow of cream from spout 28.

The substantial clearance between bore 38 of nut 36 and the periphery of spout 28 prevents 75

any cream spreading to nut 36 and dripping therefrom.

The reduction of the lower edge of spout 28 to a circular knife edge, as by rounding or beveling 35, prevents the cream accumulating on the outside of the spout and aids in shooting the cream down into the container in a substantially straight, even stream as indicated in fine broken lines at Fig. 3.

10 It will be understood that after valve 13—14 is closed and while the edge 24 of the piston head is dropping but still within smaller bore 25 of the cylinder, cream will be sucked into the upper interior of cylinder 15 from the reservoir through 15 tubular boss 4, annular chamber 16 and over the top of cylinder 15.

It will be observed that the pump may be primed even in the preferred embodiments shown in Figs. 1, 2 and 3, without using the vent 12 and 20 screw 7. For example, before placing the cover 2 in position the cylinder 15 may be filled with cream, the cover 2 placed in position and clamped with screw 7. The cylinder will contain cream but chamber 16 and the top of the housing, above 25 the top of cylinder 15, will contain air. Operation of the pump a few times will eject the air together with some cream until all air is ejected.

Also in the preferred embodiment it will be noted that the operation of the pump in ejecting 30 cream will suck cream into the housing even though the reservoir be lower than the boss 4. Obviously the lower the reservoir below boss 4, the stronger suction will be required and if the reservoir were very low and the required suction 35 correspondingly great so as to materially slow the downward movement of piston head 23, such downward movement could be easily accelerated by supplementing the weight of the piston by any simple and obvious mechanical expedient as, 40 for example, by the insertion of a compression coiled spring between the top of the piston head and the ceiling of the housing.

The operation of the modified structure illustrated at Fig. 4 is the same as that above described except that the communication between 45 the liquid reservoir and the upper interior of the cylinder is direct instead of through tubular boss 4, chamber 16 and over the top edge of the cylinder. In this form the upward movement of 50 the cylinder is not mechanically limited as by contact of lugs 17 with the ceiling of the housing as in the other form, but such upward movement stops and the cylinder drops as soon as the 55 upward movement of head 23 stops, thereby releasing the suction beneath the head.

This method of operation makes it necessary in this embodiment to have cylinder 15 made of substantial weight because, if too light, a sudden and vigorous upstroke of the piston head might cause 60 the cylinder to continue its upward movement after the piston head had reached its limit in which case the head would start on its down stroke before valve 13—14 is closed thus lessening the efficiency of the above described operation.

65 While I have illustrated and described structural details of embodiments of my invention, I do not wish to be limited thereto as various modifications of and changes in details of construction will occur to those skilled in the art and 70 within the spirit and scope of the disclosure and of the appended claims.

I claim

1. In a liquid dispensing pump, in combination, 75 a housing, a vertically reciprocable cupped cylinder within the housing, a liquid chamber

around the cylinder within the housing, an outlet in the bottom of the housing, a piston reciprocable within the cylinder, means operable through said outlet for raising the piston, passages in the bottom of the cylinder in open communication with said outlet but having means to open said passages to communication with the chamber when the cylinder is raised and to close 10 said passages against said communication with said chamber when the cylinder is at its lowest 10 position.

2. In a liquid dispensing pump, in combination, a housing, a vertically reciprocable cupped cylinder within the housing, a liquid chamber around the cylinder within the housing, an outlet in the bottom of the housing, a piston reciprocable within the cylinder, means operable through said outlet for raising the piston, said means being adapted to open said outlet during the downward movement of the piston but to 20 close said outlet under all other conditions, passages in the bottom of the cylinder in open communication with said outlet but having means to open said passages to communication with the chamber when the cylinder is raised and to close 25 said passages against said communication with said chamber when the cylinder is at its lowest position.

3. In a liquid dispensing pump, in combination, a housing, a vertically reciprocable cupped cylinder within the housing and having its bore enlarged near its bottom, a liquid chamber around the cylinder within the housing, an outlet in the bottom of the housing, a piston reciprocable within both bores of the cylinder and 35 having a liquid-tight but freely slidable fit in the smaller bore of the cylinder, means operable through said outlet for raising the piston, passages in the bottom of the cylinder in open communication with said outlet but having means 40 to open said passages to communication with the chamber when the cylinder is raised and to close said passages against said communication with said chamber when the cylinder is at its lowest 45 position.

4. In a liquid dispensing pump, in combination, a housing, a vertically reciprocable cupped cylinder within the housing, a liquid chamber around the cylinder within the housing, an outlet in the bottom of the housing, a piston reciprocable within the cylinder, means operable through said outlet and through the bottom of the cylinder for raising said piston and for centering the cylinder with the outlet, passages in the bottom of the cylinder in open communication with said outlet but having means to open 50 said passages to communication with the chamber when the cylinder is raised and to close said passages against said communication with said chamber when the cylinder is at its lowest 55 position.

5. In a device of the character described, in combination, a reciprocable piston within a reciprocable cupped cylinder within a housing, a bore through the bottom of the cylinder, a sleeve depending from the housing, a stem slidable in said sleeve and in said bore and attached to said piston, a tubular spout slidable within the sleeve, means within the sleeve for limiting downward movement of the spout, a valve seat in the top 65 of the spout and a valve on the lower end of said stem adapted to alternately open and close said valve seat.

6. In a device of the character described, in combination, a reciprocable piston within a recip- 70
